LIFESAVING DEVICE FOR SCAFFOLDS

Jack Frankel, Brooklyn, N. Y.

Application February 18, 1952, Serial No. 272,213

2 Claims. (Cl. 227—34)

1

This invention relates to a life saving device, and more particularly to a mechanism for gripping a safety rope and for being attached to the safety belt of a person working at a dangerous height.

Many occupations are hazardous due to the height at which duties must be performed. Thus a worker on a scaffold is in a dangerous position, even though the scaffold itself is safe and secure. Many men have tripped and fallen from scaffolds, or been knocked off of scaffolds by falling objects or other workers. Many scaffolds have fallen, their ropes have broken, or one side has been suddenly dropped. In such instances, having a safety belt fastened to the scaffold is no protection.

The object of the present invention is to provide a device which can be used by a man working at a height on a scaffold, ladder, window ledge or the like, which device will prevent him from falling inadvertently from his support.

A further object is to provide a device as aforesaid, which consists primarily of a hanging rope or cable, a safety belt which can be buckled about the person, and a gripping device secured to said belt for gripping the cable to secure the person thereto, which gripping device can be slid, when desired, along the cable without danger that a fall may occur during such sliding adjustment.

Another object is to provide a device as aforesaid in which the person using the device can quickly change his vertical position without losing the benefit of the safety cable, by merely squeezing two levers of the device to release the cable, the levers automatically being returned to cable-gripping position upon being released.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a man working on a scaffold and employing the life saving device of the present invention.

Fig. 2 is a front view of the cable gripping device, the safety belt being omitted and the lever shown in its locked position.

Fig. 3 is a rear view of Fig. 2, the safety belt and links being omitted.

Fig. 4 is an elevational view of the clamping jaw of the device.

2

Fig. 5 is an enlarged sectional view taken on line 5—5 of Fig. 2.

Fig. 6 is a side view of the device as viewed from the left of Fig. 2.

Fig. 7 is a side view of the stationary drum.

Fig. 8 is another side view of the drum, rotated 90 degrees from its position in Fig. 7.

Fig. 9 is a perspective view of the release arm, per se.

10 The life saving device 10, according to the present invention, is shown in the drawings used by a man 11 working on a scaffold 12. The device includes a safety belt 13 which is buckled about the man's waist.

15 The device 10 includes a thick vertical plate 14, having downwardly and laterally extending lugs 15 having suitably located orifices 16 and a vertically elongated slot 16^a in each of which is fastened a swinging link 17 carrying a spring clip 18. The two outer clips 18 are fastened to the safety belt 13 and the center clip is available for fastening to any other suitable element which it may be desired to secure to the safety cable. It may also be clipped to a "fire" belt,

20 which would be a waist-type belt to be used in lowering a person down the cable in case of fire, the device assuring that the person will not descend too rapidly or fall altogether.

The device is adapted to grip its lifeline or safety cable 19, which cable 19 will be firmly secured to some anchorage above the person working on the scaffold. For example, a scaffold is usually fastened to a building coping or guard, and the cable 19 will be similarly anchored. A guide pulley 20 is rotatably mounted on a bolt 21

25 secured at the top of the plate 14. The groove 22 of this pulley is deep enough to completely receive the cable 19, which is shown in this instance as a strong wire flexible cable. Manila rope may be employed instead of wire cable if desired.

30 Where rope is used, it will be thicker than wire cable, and consequently the pulleys used with the rope will have wider grooves 22 than the pulleys used with the wire cable. The device is, however, of the same construction except as to dimensions for either wire cable and manila rope employment.

35 The cable 19 is guided by the rolling pulley 20 to a stationary drum 23 which is secured to the center of the plate 14 by a bolt 24. The drum is best shown in Figs. 7—8. It has an arbor 25, cylindrical in shape, and an outer end flange 26. The wire cable is wrapped about the arbor. As seen in Fig. 2, the wire cable passes around the pulley 20 in a clockwise direction and about the 40 arbor in a counterclockwise direction, and is

guided to the pulley 20 by a rigid arm 27 of an elbow secured to the plate 14 by rivets 28. The drum is secured to the plate 14 by a fitting 29 and the bolt 24. Adjacent the outer and inner ends of the arbor are oppositely running cams 30. Each cam is somewhat less than 180 degrees in length, and the cams are disposed opposite each other. The inner cam has its wide end in the vertical center plane of the drum at the bottom thereof. The outer cam has its wide end at the top of the plane. The opposed faces 31 of the cams are inclined, see Fig. 8, so that the space longitudinally of the arbor between the cam is wedge-shaped for receiving the convolutions of the cable 19. The outer cam is secured to the flange 26 and the inner cam is secured to the plate 14 by bolts 32.

The cable 19 is guided over one side of the pulley 20 to the other side of the drum, see Fig. 6, and is given two and one-half turns about the drum so that it passes from the drum on the same side as its first convolution. The convolutions are squeezed between the cams in the wedge-shaped spaces, and this squeeze keeps the convolutions in place and enhances the resistance to movement of the cable produced by the friction of the convolutions on the drum arbor by assuring contact with the arbor. The more cable turns over the drum, the more force will be required to move the device relative to the stationary cable. The cams guide the cables into convolutions. If a dead weight, as a man falling, was imposed on the cable, stretching same, the "squeeze" in the wedge-shaped spaces would be reduced. The bottom edge of the inner cam forms a shoulder which rubs with friction contact against the cable.

Below the drum is another guiding roller 20, in line with but inwardly of the top guiding roller, and this roller at the bottom guides the cable to a clamp 33. Clamp 33 has a stationary jaw 34 and a movable jaw 35. Jaw 34 is secured to plate 14 by several bolts 34a, see Figs. 3 and 5. It has a portion the thickness of plate 14 superposed thereon and a thicker portion which underlies the plate 14, see Fig. 6. The jaw 34 has a vertical groove 36 for receiving the cable 19, see Fig. 5. Jaw 35 has a groove 37 mating with groove 36. This jaw is superposed on the plate 14 and slides thereon.

Jaw 35 includes an arcuate leg 38 which slides on the plate 14 and is maintained thereon by a curved slot 39 working on two spaced bolts 40 screwed into the plate 14. The leg has a large slot 41 disposed over a post 42 secured to the plate 14. This post serves as an anchorage for a coil compression spring 43, the other end being anchored against a shoulder 44 of the leg 38. The coil spring is maintained in place by a curved rod 45 extending from the shoulder 44, see Fig. 4. At the top of the leg is an elongated hole 46 engaged by a pin 47a of a pivoted bell crank lever 47. This bell crank lever 47 is fulcrumed on a pin 48 carried by a depending handle 49 rigidly secured to the plate 14. At its lower end the handle 49 carries a swinging link 50 and lever 47 has a notch 51 at its lower end. When lever 47 is swung toward handle 49, the link is adapted to fit in the notch 51, preventing the lever from being swung away from the handle 49 by the spring 43.

At its free end, the release arm 60 has a right angularly extended bill portion 62 which extends rearward over the top of the link 50. The bill portion 62 has a lower cam surface 62a ar-

ranged to ride on the link 50 and cause it to be pivoted downward out of the notch 51 to release the lever 47 whenever downward movement of the link 17 takes place with relation to the lug 15 having the vertically elongated slot 16a. Release of the lever 47 frees the movable jaw 35 to be urged by the spring 43 into a position gripping the cable 19.

The operation of the device is as follows: Assuming that the device is to be used by a man working at a height on a scaffold, it being understood that the device is equally applicable to other uses, the cable 19 is first secured at its upper end, as aforesaid, and fastened to the device with as many turns on the drum as is necessary to bring the drum cams into wedging action. The device is secured to the man's safety safety belt, the lever and handle are gripped and squeezed, the link 50 is engaged with the notch 51 holding the movable jaw 35 in an inoperative position. The cable 19 is pulled downwardly below the device until all slack has been taken up. The full movement of the lever by squeezing it toward the handle 49 slides the leg 38 upwardly along the screws 40 and moves the jaw portion 33 of the movable jaw 35 away from the jaw 34, the spring 43 being compressed by this movement. The cable 19 is accordingly released.

Of course the scaffold will be changed as to its vertical position from time to time. For instance, if a workman is painting a sign on a wall, he will ordinarily work from the top and drop the scaffold as his work proceeds. It is during dropping of the scaffold that the greatest risk of accident occurs. For example, the scaffold is usually held in place by ropes at its ends working over pulleys, the ropes being tied to the scaffold. To drop the scaffold, the rope at one end is untied, and this end of the scaffold is first dropped, assuming one man only is working on the scaffold. The scaffold is then tilted dangerously until the other end is similarly dropped. During the release of the rope, if the man should lose his grip on the rope, the scaffold would drop vertically and be held at one end. This, of course, would be very dangerous. But even if no accident such as the above occurs, the tilting of the scaffold still presents danger, as the man must climb this tilted hanging walk to get to the other end. The life saving device eliminates any danger during this operation.

The normal use of the device, assuming that the lowering of the scaffold proceeds safely, permits the lowering of the device along the cable the same distance as the scaffold was lowered without at any time taking the device out of operation. That is to say, at no time is the life saving feature of the device nullified. During such normal operation the cable slides past the open jaws 34 and 35 with the cable 19 turning reluctantly around the drum 23, maintaining fairly tight engagement therewith. Should the man fall during this operation, downward movement of the plate 14 relative to the cable 19 would be impeded by the engagement of the cable 19 with the drum 23. The links 17 would be pulled downward relative to the plate 14 by reason of their engagement with the safety belt 13 causing the link 17 which engages the vertically elongated slot 16a to move downward relative to the respective lug 15 and pivot the release arm 60 downward causing its bill portion 62 to swing the link 50 downward disengaging it from the notch 51 to release the lever

47, which would be a natural incident to a fall, and such release will permit the return of the jaw 33 into tight cable-engaging relation with the jaw 34, thus checking the fall.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A life saving apparatus for preventing a man from accidentally falling from a high perch comprising, a cable adapted to be rigidly connected at its upper end to an anchorage, a safety belt adapted to be worn by the man, and a device for adjustably securing said belt to said cable, said device including a vertical plate including a rigid stationary jaw secured to said plate, a guide secured to said plate, a post secured to said plate, a sliding jaw mounted on said guide and post, said jaws having mating grooves for said cable, a coil spring compressed between said post and a part of said sliding jaw for urging said sliding jaw toward said stationary jaw, a lever fulcrumed to said plate and connected to said sliding jaw for moving same away from said stationary jaw against the resistance of said spring, a rigid handle secured to said plate for use in manually moving said lever, said handle having a link for coacting with said lever for locking said lever in a retracted position of said sliding jaw, and release means for disengaging said link from said lever to free said sliding jaw to be urged into operative position with relation to said stationary jaw when the man wearing the safety belt starts falling, said release means comprising a pivotally mounted release arm having a bill portion engaging said link, and means controlled by the attachment of said plate to said safety belt for piv-

oting said release arm to free said link from said lever.

2. A life saving apparatus for preventing a man from accidentally falling from a high perch comprising, a cable adapted to be rigidly connected at its upper end to an anchorage, means to secure a man to said cable, said means comprising, a vertical supporting plate, and a gripper including a rigid stationary jaw secured to said plate, a guide secured to said plate, a post secured to said plate, a sliding jaw mounted on said guide and post, said jaws having mating grooves for said cable, a coil spring compressed between said post and a part of said sliding jaw for urging said sliding jaw toward said stationary jaw, a lever fulcrumed to said plate and connected to said sliding jaw for moving same away from said stationary jaw against the resistance of said spring, a handle secured to said plate, said handle having a link for coacting with said lever for locking said lever in a retracted position of said sliding jaw, and release means for disengaging said link from said lever to free said sliding jaw to be urged into operative position with relation to said stationary jaw when the man wearing the safety belt starts falling, said release means comprising a pivotally mounted release arm having a bill portion engaging said link, and means controlled by the attachment of said plate to said safety belt for pivoting said release arm to free said link from said lever.
